UNIVERSAL DRILL PRESS AND PIPE VISE
Ralph L. Hustead, General Delivery, Chicago 7, Ill.
Filed July 12, 1963, Ser. No. 294,681
1 Claim. (Cl. 269—208)

Object

The object of this invention is to provide a vise that has several uses of holding different sizes and shapes of material. An object is to provide a vise that has a quick adjustment of jaws. Still another object is to provide a vise that replacement of parts can easily be made.

A very important object is to provide a vise that is very economical for the buyer.

Brief description

FIGURE I is a top view of the universal vise showing a one half scale drawing of a small size vise. This top view shows how strong the design is, as well as being simple. This top view shows use of conventional materials used in this new vise which keeps the cost to a minimum.

FIGURE II is a side view of the vise.

FIGURE III is a sectional view of vise jaw, showing locking device entirely enclosed in adjustable vise jaw.

Detailed description

In FIGURE I, 1 is a plate of steel, this plate is the base on which the entire vise assembly is attached. The end jaw is 2, this jaw is of conventional angle and has two holes drilled in the corners of the jaw and on through base plate 1. This end jaw 2 is attached to base plate by two rivets 3. Rear stabilizer 4 has two holes drilled horizontally that receive the two bars 6. At either end of stabilizer 4 are two drilled holes 5, also holes are drilled through the base plate to correspond with holes 5. Rivets hold stabilizer 4 to base plate 1 going through hole 5. Two round or cylindrical bars 6 extend the entire length of vise. These bars pass through holes in the end jaw, then through floating jaw 10 and continue through stabilizer 4. As to the construction of such bars, threads are cut at the front end of each bar, spacer 8 encloses the threads and provides a thrust for nut 9. Holes 7 equally spaced in bars 6 are for quick adjustment of the floating jaw 10.

Two nuts 9 provide clamping for the floating jaw 10. Therefore clamping pressure holds flat, or round material between jaws 10 and 2. Hole 17 is cut out of base plate to provide a way to hold long material to be drilled at 50 its end.

Floating jaw 10 has two drilled holes 18 these holes correspond with holes drilled in bars 6. Two pins 14 slip fit down through floating jaw 10 and on through

2

bars 6, this provides the necessary attachment of floating jaw 10 to bars 6 and gives movable action when nuts 9 are turned, either way, for either holding or releasing materials between jaws 10 and 2. Floating jaw 10 is easily and quickly adjusted for different size materials by the removal of two slip pins 14, the floating jaw slides on bars 6 to the desired position and slip pins 14 are inserted again.

Floating jaw 10 has cuts on either side to hold different shaped materials. This jaw is easily and quickly reversed for needs of material to be held. Slip pins 14 are removed, bars 6 are pulled out from stabilizer 4 and out of floating jaw 10, the jaw is then reversed or another jaw inserted and the bars 6 are again positioned in the holes of floating jaw 10 and stabilizer 4.

In this top view the front side of jaw has a step 11 cut out to hold flat, square or rectangular material. On back side of jaw horizontal V, 13 and vertical V 12 are cut to hold round material. On jaw not shown vertical V 12 is a step V cut used to hold pipe.

Two holes 15 and 16 are for bolts, when vise is to be attached to a surface for heavy drilling and pipe cutting or threading.

According to the provisions of the patent statutes, I have explained the principle of my invention and have illustrated and described what I now consider to represent its best embodiment. However, I desire to have it understood that, within the scope of the appended claim, the invention may be practiced otherwise than as specifically illustrated and described.

I claim:

A vise comprising a base member, a fixed jaw on said base, guide clamping rods removably and slideably received in said fixed jaw, each rod having spaced locking holes therein, an adjustable, reversible jaw having holes receiving said rods, said adjustable jaw having opposite clamping surfaces of different configurations and locking holes selectively alignable with the rod locking holes, pin members disposed in aligned locking holes of said jaw and rods and means engaging said rods for moving said rods and said adjustable jaw into clamping relation with said fixed jaw.
